AUTOMATIC RETRIEVAL CARD FILE

John G. Brueggeman, Cincinnati, Ohio, assignor to The Mosler Safe Company, Hamilton, Ohio, a corporation of New York

Filed Apr. 29, 1963, Ser. No. 74,658

Term of patent 14 years

FIGURE 1 is a perspective view of the automatic retrieval card file showing my new design. The opposite side and rear, which are not shown in this figure, are mirror images of the front and side shown.

I claim:

The ornamental design for an automatic retrieval card file, substantially as shown and described.
